AIR CONDITIONING SYSTEM

Clarence W. Nessel, Dayton, Ohio, assignor to
 Minneapolis-Honeywell Regulator Company,
 Minneapolis, Minn., a corporation of Delaware

Application August 30, 1937, Serial No. 161,591

11 Claims. (Cl. 236—11)

This invention is directed to a fluid circulating system and more particularly to a heating system.

In a building having a plurality of spaces or zones to be heated, it is common to provide a 5 warm air furnace connected by ducts to the various spaces to be heated, and a blower for circulating air through the furnace and through said spaces. In order to control the temperature in each space individually, each space may be 10 provided with a thermostat, and a damper motor under the control of each thermostat, for operating dampers in the various warm air ducts, to permit or prevent the flow of air into each space, depending upon whether the thermostat in the 15 particular space is calling for heat or is satisfied.

In such a system, it is unnecessary to circulate air at as fast a rate when only one space is calling for heat as when more than one space is calling for heat. I therefore provide automatic 20 means to operate the blower to circulate air at one rate when only one space is demanding heat, and to operate the blower to circulate air at a higher rate when more than one space is demanding heat, and also to stop the blower when 25 none of the spaces are demanding heat, since, when none of the spaces are demanding heat, all the warm air ducts are closed by their respective dampers, and there is no necessity or advantage in operating the blower at this time.

30 It may happen that one space in the building is larger than the others, or for some other reason, such as its exposure, may require a larger amount of heat to raise its temperature, and accordingly, I have provided means to operate 35 the blower to circulate air at a higher rate when this particular space is calling for heat than when any other one space is calling for heat.

I have illustrated two common means for varying the amount of air circulated by the blower, 40 but it should be understood that my invention is not limited to the two ways illustrated. In one form of the invention, a two-speed fan is illustrated, and in another form, adjustable dampers controlling the input to the fan are provided.

45 While my invention is illustrated in connection with a warm air heating system, it is equally applicable to any other type of heating system such as a hot water heating system, and to any other fluid circulating system, such as a cooling, 50 ventilating, or humidity controlling system, and it should therefore be understood that it is not limited to a warm air heating system.

55 One of the objects of my invention is, therefore, to provide an improved fluid circulating system.

Another object of my invention is to provide a fluid circulating system wherein fluid is circulated at varying rates of flow in accordance with the number of spaces being supplied with fluid. 5

Another object of my invention is to provide a fluid circulating system wherein fluid is circulated at different rates of flow in accordance with the size and/or number of spaces being supplied with fluid. 10

More specifically, it is an object of my invention to provide a warm air heating system wherein a plurality of spaces are to be heated, and wherein one space requires more heat than the others, with thermostatic means for controlling the flow of air to the various spaces, together with means for circulating air at a high rate when any two spaces, or the aforementioned one space is calling for heat, for circulating air at a low rate when any other single space is calling for 20 heat, and to stop the air circulation when none of the spaces are calling for heat. 15

Other objects will become apparent upon a study of the specification, claims and appended drawings, in which like reference characters represent like parts in the different views, and in which: 25

Figure 1 is a schematic view of one form of my invention, 30

Figure 2 is a view of a second form of my invention, and 35

Figure 3 is a view of still another form of my invention.

Referring now to Figure 1 a heating plant is 35 illustrated, said plant comprising a warm air furnace 10 having a fuel supply line 11, a warm air duct 12 having branch ducts 13, 14, 15, and 16, communicating with registers 17, 18, 19, and 20 located in the spaces to be heated. A fan 21 40 is provided for circulating air through the furnace and spaces to be heated, there being a return air duct 22 communicating with the inlet of the fan. The furnace is also provided with the usual flue gas stack 27. 45

For driving fan 21, I have provided a motor 23 connected to the fan by means of a belt 24, said belt travelling over pulleys 25 and 26 on the motor and fan, respectively. The motor 23 is of the condenser induction type and comprises an 50 armature 30, a field winding 31, a second field winding 32, and a condenser 33. Windings 31 and 32 are connected together at one end thereof and condenser 33 is connected to the other end of winding 32. An autotransformer 35 is pro- 55

vided for varying the current through winding 23, thereby varying the speed of the motor.

In the fuel supply line 11 is a valve 38, said valve having an upstanding stem 39 to which is connected an armature 40, this armature being surrounded by a solenoid 41. Energization of solenoid 41 causes armature 40 to move upwardly and through the stem 39 causes the valve to move to open position. Any suitable means such as a spring (not shown) may be provided for moving the valve to closed position when solenoid 41 is deenergized.

Mounted in the warm air chamber of the furnace is a bimetallic element 42 connected at one end to a rod 43, the other end of said element 42 being held against movement by being rigidly connected to the wall of the furnace or otherwise suitably secured against movement. The rod 43 is connected to the mercury switches 44 and 45 in a known manner, so that rotation of rod 43 by the bimetallic element 42 causes switches 44 and 45 to be tilted. Switch 44 is provided with contacts 46 and 47, and switch 45 is provided with contacts 48 and 49. Switch 45 is designed to be closed at a lower temperature than is necessary to close switch 44.

For controlling the operation of the motor 23 and the energization of solenoid 41, a relay generally indicated by the reference character 60 is provided. This relay comprises a coil 61, an armature 62, switch arms 63 and 64, and stationary contacts 65 and 66 cooperating with the switch arms 63 and 64, respectively. When coil 61 is energized, switch arms 63 and 64 are moved out of engagement with their respective contacts 65 and 66, and when deenergized the switch arms move into engagement with their respective contacts.

For controlling the speed at which motor 23 operates there is provided a second relay generally indicated by the reference character 50. This relay comprises a coil 51, armature 52, a switch arm 53, and contacts 54 and 55. When coil 51 is deenergized, switch arm 53 is in engagement with contact 55, and when said coil is energized the arm 53 is moved into engagement with contact 54.

For supplying power to the relays I have provided a transformer 70, said transformer having a high tension coil 71 and a low tension coil 72, the high tension side of the transformer being connected to lines 73 and 74 which are in turn connected to a suitable source of power (not shown).

55 The spaces to be heated are designated by the reference characters 80, 100, 120, and 140 and located in each of these spaces are thermostats 81, 101, 121, and 141. These thermostats comprise bimetallic elements 82, 102, 122, and 142, contact carrying arms 83, 103, 123, and 143, respectively, and fixed contacts 84, 104, 124, and 144 cooperating with the respective arms.

Controlled by each of these thermostats is a damper motor of which only one has been illustrated, in the space 140. This damper motor comprises an armature 147 and a field coil 148. Armature 147 drives through suitable reduction gearing 149, cams 150 and 151 carried on a shaft 160. Carried by the end of shaft 160 is a crank 158 which is connected to a link 159, in turn connected to arm 161 the other end of which is connected to a damper 145 located in the register 20. Rotation of shaft 160 through 180° from the position shown causes damper 145 to move to open position, the amount of movement of the motor

being limited by the bottom of the slot 162 in which arm 161 travels. This damper motor operates until the damper is in wide open position, at which point it stalls, and maintains the damper in this position until the energizing circuit to the motor is broken. A spring 163 is provided for returning the damper and the motor to its original position after it has been deenergized.

Cams 90, 91, 110, 111, 130, and 131 similar to cams 150 and 151 in space 140, are located in spaces 80, 100, and 120 as shown. Cooperating with the various cams are switch arms 92, 93, 112, 113, 132, 133, 152, and 153, these switch arms being held in engagement with contacts 94, 95, 114, 115, stop 134, contact 135, stop 154, and contact 155, respectively, when the damper motors in each space are deenergized. When the cams are rotated through 180° the respective switch arms are moved into engagement respectively with contacts 96, 97, 116, 117, 136, 137, 156, and 157, and in this position, the dampers in the respective spaces are wide open.

OPERATION OF SPECIES OF FIGURE 1

With the parts in the positions illustrated 25 none of the thermostats in the various spaces are calling for heat, the blade of each thermostat being out of engagement with its respective contact. Relay coil 61 is energized, thereby holding switch arms 63 and 64 out of engagement with contacts 30 65 and 66, the energizing circuit for this relay being as follows: from one side of low tension coil 72 of transformer 70 through conductors 200, 201, switch arm 93, contact 95, conductor 202, switch arm 113, contact 115, conductor 203, switch arm 35 133, contact 135, conductor 204, switch arm 153, contact 155, conductor 205, through the coil 61 and conductor 206 to the other side of transformer coil 72. Since switch arms 63 and 64 are out of engagement with their respective contacts 40 it will be apparent that there is no circuit through solenoid 41 or motor 23.

Should the thermostat in any one of the spaces call for heat a circuit through the respective damper motor is established. Assume the thermostat in space 80 is calling for heat, the damper motor in this space will be energized by the following circuit: from line 74 through conductors 170, 171, 172, 173, 188, bimetallic element 82, arm 83, contact 84, conductor 180 through the field 50 coil of the motor, and conductors 181, 182, 183, and 184 back to the line 73. It will be obvious that the damper motor in any of the other spaces will be energized through a similar circuit upon a call for heat by the thermostats in those spaces. 55

Energization of the damper motor in space 80 causes rotation of cams 90 and 91 through 180°, at which time the damper in said space is in open position and further movement is prevented, as described in connection with the damper motor 60 146 and damper 145. Switch arms 92 and 93 are now in engagement with contacts 96 and 97 as will be apparent. The circuit through relay coil 61 is now broken by reason of the opening of contact 95, whereupon switch arms 63 and 64 move 65 into engagement with their respective contacts 65 and 66. It will be obvious that the energization of any of the damper motors with the attendant shifting of the respective switch blades will likewise cause relay coil 61 to become deenergized. 70

Engagement of switch blade 63 with contact 65 causes a circuit through solenoid 41 as follows: from line 74 through conductor 210, switch arm 63, contact 65, conductor 211, solenoid 41, and conductor 212 back to the line 73. Energization 75

of solenoid 41 causes opening of valve 38 as previously described whereupon fuel is supplied to the furnace 10 through pipe 11, the furnace thereby becoming hot.

5 When the temperature rises a sufficient amount in the heating chamber of the furnace, bimetallic element 42 causes switch 45 to tilt whereupon the contacts 48 and 49 are closed by the mercury therein and energy is supplied to 10 motor 23. Autotransformer 35 is connected to the source of power from the line 74, through conductor 215, contacts 48 and 49 of switch 45, conductor 216, contact 66, switch arm 64, conductor 217, tap 218 on the transformer through 15 the transformer coil to tap 219, and through conductors 220, 221 to line 73. Relay 51 is at present deenergized, and switch 53 is in engagement with contact 55, and the voltage impressed on coil 31 is less than that impressed on the 20 transformer, current flowing through the coil 31 through the following circuit: from the coil 31 through conductors 225, 220, terminal 219 of the transformer, through part of the transformer 25 35 to the tap 224, through conductor 226, contact 55, switch arm 53, and conductor 227 to the other side of field winding 31. Field winding 32 and condenser 33 is connected to the transformer through the following circuit: from terminal 219 of the transformer, through conductors 220 and 225, coil 32, condenser 33, to terminal 222 of the transformer. The motor now 30 operates at low speed since the voltage on field winding 31 is considerably less than the line voltage.

35 When relay coil 51 is energized and switch blade 53 is moved into engagement with contact 54 the voltage across coil 31 is increased whereupon the motor travels at high speed. The voltage on coil 31 is now greater than line voltage, 40 the coil now being connected to transformer 35 as follows: from the field winding 31 through conductors 225, 220, terminal 219 of the transformer, through part of the transformer to tap 223, conductor 228, contact 54, switch arm 53, and conductor 227 to the other side of field winding 31. It is therefore apparent that the 45 voltage on coil 31 is increased upon energization of relay coil 51 and that the motor will operate at high speed.

50 Assume now that any other space also requires heat, as for example, space 120, the energization of the damper motor for this space causes cams 130 and 131 to move through 180° whereupon switch arms 132 and 133 are in engagement with contacts 136 and 137. After the 55 temperature of the furnace rises to a high predetermined value at which contacts 46 and 47 are closed by the tilting of switch 44 a circuit through relay coil 51 is established, this circuit being as follows: from the low tension coil 72 of transformer 70 through conductors 200, 201, switch arm 93, contact 97, conductors 190, 191, 194, contact 137, switch arm 133, conductor 203, contact 115, switch arm 113, conductors 202, 244, 60 contact 98, switch arm 92, conductors 230, 232, contacts 46, 47, conductor 233, relay coil 51, and conductor 234 back to the low tension coil 72. Energization of relay coil 51 causes switch arm 53 to move into engagement with contact 54, 65 whereby the high speed circuit through the motor, previously described, is established, and the motor drives the fan at high speed.

A call for heat by any combination of two zones will cause the energization of coil 51 through a circuit similar to that described above.

Zone 140 is what is termed a "Master zone." That is, it may require more air to be circulated therethrough when there is a call for heat therein than any of the other zones, either by reason of its size or its exposure, for example. For this 5 reason a circuit is established through relay coil 51 should this space alone require heat. When switch arm 143 of thermostat 141 moves into engagement with contact 144, cams 150 and 151 are rotated through 180°, as previously described, 10 moving switch arms 152 and 153 into engagement with contacts 156 and 157, thereby establishing the following circuit through relay coil 51, it being assumed that the temperature of the furnace has risen to the value in which contacts 46 15 and 47 are closed, this circuit being as follows: from the low tension coil 72 through conductors 200, 241, contact 156, switch arm 152, conductors 231, 232, contacts 46, 47, conductor 233, through relay coil 51 and conductor 234 to the 20 other side of low tension coil 72.

It will therefore be seen that upon a call for heat in any one zone, that the supply of fuel to the furnace is started. It will also be seen that upon a call for heat by any single zone with 25 the exception of zone 140 that the motor 23 is operated at low speed, after the switch 45 has closed because of a sufficient rise in temperature of the furnace, and that a call for heat by any two zones, the motor 23 is operated at high speed, 30 assuming that switch 44 has been moved to closed position. It has also been pointed out that upon a call for heat by zone 140 alone the motor is operated at high speed. When all of the thermostats have become satisfied the damper motors 35 are returned to their original positions as illustrated under the influence of their respective springs such as spring 163 of damper motor 146, whereupon relay coil 51 is again energized through the circuit originally described, switch 40 arms 63 and 64 are moved to open positions, the supply of fuel to the furnace is cut off by reason of the deenergization of solenoid 41, relay coil 51 is deenergized and the supply of power to the motor 23 is cut off by the opening of switch 64. 45

Description of Figure 2

In Figure 2 I have illustrated a system similar to that of Figure 1 except that a single speed fan motor is provided and the change in rate 50 of circulation of air is controlled by suitable dampers provided in the return air duct 22 to the fan 21.

The motor is represented by the reference character 250 and is provided with contacts 313 55 and 314, said motor being connected to the fan by a belt 24 passing over pulleys 25 and 26 of the motor and fan, respectively.

In the return air duct are shown dampers 260, connected to a damper motor 261 by means of 60 link 262 pivotally connected at its other end to arm 263 connected to a shaft 264 which is driven by the motor 261. Stops 265 and 266 are provided to limit the movement of arm 263, a spring 267 moving arm 263 against stop 266, arm 263 65 being held against stop 265 in which position the dampers 260 are in their wide open position when the motor is energized.

Switches 44 and 45 operated by the bimetallic element 42 are identical with those described in 70 Figure 1. A third switch 251 operated by the bimetallic element 42 is provided for a purpose to be later described, this switch being provided with contacts 252 and 253 which are normally closed and which are opened when the tempera- 75

ture of the furnace reaches a high predetermined value, said value being higher than that required to close switches 44 and 45.

The damper motors and controlling means therefor are identical with those shown in Figure 1 and for this reason have not been illustrated in this figure.

OPERATION OF SPECIES OF FIGURE 2

10 With none of the zones requiring heat, relay coil 61 is energized through the following circuit: from low tension coil 72 of transformer 70 through conductors 304, 303, switch arm 93, contact 95, conductor 302, switch arm 113, contact 115, conductor 301, switch arm 133 and contact 135, conductor 300, switch arm 153, contact 155, and conductor 205 through relay coil 61 and conductor 206 back to the other side of transformer coil 72.

20 Switch arms 63 and 64 are accordingly held out of engagement with the contacts 65 and 66 and no current flows to the solenoid 41 or motor 250.

Upon a call for heat in any one of the zones the damper motor for that particular zone operates to open the damper in the register for that zone whereupon the cams are rotated through 180° thereby breaking the energizing circuit for relay coil 61. Solenoid 41 is now energized through the following circuit: from line 74 through conductor 210, switch arm 63, contact 65, conductor 211, solenoid 41, conductor 212, contacts 252, 253 and conductor 212 back to line 73. Fuel is now supplied to the furnace 10 whereupon the temperature is increased until switch 45 is tilted to close contacts 48 and 49 and current through motor 250 flows as follows: from the line 74 through conductor 310, contacts 48, 49, conductor 311, contact 66, switch arm 64, conductor 312, terminal 313 through the motor winding, terminal 314 and conductor 315 back to the line 73.

40 It is therefore apparent that upon a call for heat by any one zone fuel is supplied to the furnace and after a predetermined rise in temperature in the heating chamber thereof motor 250 operates to circulate air through the furnace and through the space in which the damper has been opened, or the space requiring heat. The amount of air circulated is at a low value as long as damper motor 261 is deenergized, holding dampers 260 in the positions as illustrated.

50 Should there be a call for heat in any two or more zones the damper motor 261 will be energized, or if zone 80 alone, this zone being the "master zone" in this modification, is requiring heat, the damper motor 261 will be operated. Assume for the present that zones 100 and 120 require heat. It will be understood that cams 110, 111, 130, and 131 have been rotated through 180° by their respective damper motors. If switch 44

60 has been tilted to close contacts 46 and 47 because of a sufficient rise in temperature in the heating chamber of the furnace, damper motor 261 will be energized through the following circuit: from low tension coil 72 through conductors 304, 303, switch arm 93, contact 95, conductor 302, switch arm 113, contact 117, conductors 331, 335, 332, contact 137, switch arm 133, conductors 301, 340, contact 116, switch arm 112, conductor 331, contact 94, switch arm 92, conductor 321, contacts 46, 47 of switch 44, conductor 322 through the damper motor 261 to conductor 323 and back to the other side of low tension coil 72. A similar circuit may be traced through the damper motor when any combination

75 of two zones is calling for heat.

Assume now that zone 80 alone is calling for heat, this zone being the "master zone," the damper motor 261 is operated to move the dampers 260 to the open position, the circuit through the motor now being as follows it being understood of course that cams 90 and 91 have been rotated through 180°: from the low tension coil 72 through conductors 304, 320, contact 96, switch arm 92, conductor 321, contacts 46 and 47 of switch 44, conductor 322 through the damper motor, conductor 323 to the other side of low tension coil 372. It is assumed, of course, that the temperature of the heating chamber is sufficiently high to cause switch 44 to be tilted to closed position.

15 Switch 251 is designed to open the circuit through solenoid 41 whereupon the flow of fuel to the furnace is cut off, upon the attainment of a high predetermined temperature in the furnace and is designed to prevent the furnace from becoming too hot.

20 It will thus be seen that the system illustrated in Figure 2 is similar to that shown in Figure 1 except that the two-speed motor illustrated in Figure 1 is substituted by a single speed fan motor and a damper motor by means of which the amount of air supplied to the fan may be varied.

Description of Figure 3

25 The structure shown by this figure is identical with that shown in Figure 1 except that in this figure the parts are so connected that no one zone alone will cause high speed operation of motor 23. In other words, the master zone has been eliminated and substituted by a zone which is similar to the others. It is believed that further description of the apparatus shown is unnecessary in view of its similarity to Figure 1.

OPERATION OF SPECIES OF FIGURE 3

30 Solenoid 41 controlling the operation of valve 40 38 is energized as in Figure 1 when relay coil 61 is deenergized. The energizing circuit for this coil when none of the zones are calling for heat is as follows: from low tension coil 72 through conductor 400, switch arm 93, contact 96, conductor 45 401, switch arm 113, contact 115, conductor 402, switch arm 133, contact 135, conductor 403, switch arm 153, contact 155, conductor 411 through coil 61 and back through conductor 420 to the other side of low tension coil 72. This circuit is broken upon the moving of any one of the above named switch arms away from its respective contacts, which takes place when there is a call for heat in any one of the zones, whereupon coil 61 is deenergized and a circuit through solenoid 41 identical to that described in Figure 1 is established. The motor 23 is now operated at low speed, assuming that switch 45 has been tilted to the position in which contacts 48 and 49 are closed by reason of the attainment of a predetermined temperature in the heating chamber of the furnace, and will continue to thus run as long as switch 64 is in engagement with contact 66 and switch 53 is in engagement with contact 55. The motor runs at high speed only when relay coil 51 is energized thereby moving switch arm 53 into engagement with contact 54 as in Figure 1. This will not take place until at least two of the zones are calling for heat, there being no single zone that when calling for heat will establish a circuit through this coil. If any two zones, as for example, zones 80 and 140 are calling for heat cams 90, 91, 150, and 151 are moved through 180° and a circuit is established through coil 51 as follows, it being assumed that switch 44 75

has been tilted to close contacts 46 and 47 by the bimetallic element 42; from the low tension coil 72 through conductor 400, switch arm 93, contact 97, conductors 412, 416, 417, 418, 415, contact 157, 5 switch arm 153, conductor 403, contact 135, switch arm 133, conductor 402, contact 115, switch arm 113, conductors 401, 407, contact 95, switch arm 92 through conductor 435, contacts 48 and 47 of switch 44, conductor 233, relay coil 51, 10 and conductor 234 back to the other side of coil 72. The energization of coil 51 will cause movement of switch arm 53 into engagement with contact 54 and cause operation of the motor at high speed as described in connection with Figure 1.

One more illustrative circuit will be traced through the relay coil 51. Assuming now that zones 80 and 120 are calling for heat, the circuit through the coil 51 is now as follows: from transformer 72, conductor 400, switch arm 93, contact 97, conductors 412, 416, 417, 414, contact 137, switch arm 133, conductor 402, contact 115, switch arm 113, conductors 401, 407, contact 95, 20 switch arm 92, conductor 435, contacts 48, 47, conductor 233, relay coil 51 and conductor 234 back to the other side of transformer coil 72.

It is therefore seen that I have devised a warm air heating system wherein damper motors to the various zones to be heated are under control 30 of separate thermostats in each zone and wherein air is circulated at a low rate in response to a call for heat in any single zone, and is circulated at a high rate upon a call for heat for more than one zone. Also a master zone may be provided which 35 causes operation of the air circulating means at a high rate upon a call for heat by that zone. It will be obvious that my invention is capable of many modifications and I wish it to be understood that the invention is to be limited only by 40 the scope of the appended claims.

I claim as my invention:

1. In a heating system, a heating chamber, means for heating said chamber, means for causing a forced circulation of fluid through said 45 chamber and through a plurality of spaces to be heated at a plurality of predetermined rates of flow, temperature responsive means in each space, means controlled by the temperature responsive means for controlling the flow of fluid into each 50 space, a plurality of electrical circuits for controlling the rate of flow of fluid by the circulating means, means responsive to the operation of the flow control means when said means is operated to admit fluid to any one space only to energize 55 one electrical circuit to cause operation of the fluid circulating means at a predetermined low rate of flow, means responsive to the operation of the flow control means when said means is operated to admit fluid to more than one space 60 to energize a second electrical circuit to cause operation of the fluid circulating means at a predetermined high rate of flow, and means whereby all the energizing circuits to the fluid circulating means are deenergized when none of the temperature responsive means are calling for heat.

2. In a heating system, a heating chamber, means to supply heat to said chamber, means to cause a forced circulation of fluid through said chamber and into a plurality of spaces to be heated at any one of a plurality of predetermined rates, means to control the flow of fluid to the various spaces, there being one space having greater heat requirements than the other spaces, means responsive to the operation of the flow control 70 means to admit fluid to the last mentioned space

to cause operation of the fluid circulating means at a high predetermined rate, means responsive to the operation of the flow control means to admit fluid to any other single space to cause operation of the fluid circulating means at a low predetermined rate, and means responsive to the operation of the flow control means to admit fluid to any two spaces to cause operation of the fluid circulating means at a high predetermined rate. 10

3. In a heating system, a heating chamber, means to supply heat to said chamber, means to cause a forcible circulation of fluid through said chamber and into any one or more of a plurality of spaces selectively at different predetermined rates dependent upon the spaces to be heated, means for controlling the flow of fluid into the various spaces, means for operating the fluid circulating means at a low predetermined rate in response to the operation of the flow control 15 means to admit fluid to any one space only, means for operating the fluid circulating means at a high predetermined rate in response to the operation of the flow control means to admit fluid to more than one space, and means for stopping 20 operation of the circulating means and the heating means in response to the operation of the flow control means to prevent flow of fluid to any of the spaces. 25

4. In an air circulating system, a fan for circulating air into a plurality of spaces, a motor for operating said fan, said motor having high speed and low speed circuits, means for controlling the flow of air into said spaces, one of said 30 spaces requiring a greater flow of air than any of said other spaces, means energizing a high speed circuit of the motor in response to operation of the controlling means to cause flow of air to the last mentioned zone, means energizing a low speed circuit of the motor in response 35 to operation of the controlling means to cause flow of air to any other single zone, and means energizing a high speed circuit of the motor in response to operation of the controlling means to cause flow of air into any two spaces. 40

5. In an air circulating system, means for circulating air into a plurality of spaces, a damper movable between two positions for varying the output of said air circulating means, in one position of which the damper permits minimum 45 air flow and in the other position of which it permits maximum air flow, means for controlling the flow of air to the various spaces; means responsive to movement of the air flow controlling means to a position causing air flow into any 50 one space only for causing operation of the air circulating means and for positioning the damper in the position of minimum air flow, means responsive to movement of the air flow controlling means to a position causing flow of air in 55 more than one space for causing operation of the air circulating means and for positioning the damper in the position of maximum air flow, and means for stopping the air circulating means when the air flow controlling means is in a position preventing flow of air into any of the spaces. 60

6. In a heating system, a plurality of spaces to be heated, a heater, circulating means for circulating fluid through the heater and through the spaces to be heated at varying rates of flow, 70 means controlling the flow of fluid into each of said spaces, a motor for operating each of said controlling means, temperature responsive means in each space for controlling the operation of the motor in that space, switch means operated by 75

each of said motors, means normally maintaining the circulating means inoperative when none of the motors are operated to admit circulation of heating fluid through said spaces, circuit 5 means for causing said circulating means to operate to circulate fluid at a low rate of flow in response to the actuation of the switch means by one of said motors when said motor is actuated to admit circulation of fluid to the space controlled 10 by said motor, and circuit means for causing operation of said circulating means to operate to circulate fluid at a high rate of flow in response to the actuation of the switch means by any two or more of said motors when said motors are actuated to admit circulation of fluid through the 15 respective spaces.

7. In a heating system, a plurality of spaces to be heated, a heater, a two-speed fan for circulating air through the heater and the spaces 20 to be heated, dampers for controlling the flow of air into each of said spaces, motors for operating said dampers, temperature responsive means in each space for controlling the motor in that space, switch means operated by each damper 25 motor, means normally maintaining the fan inoperative when none of the damper motors are operated to open their respective dampers, circuit means for establishing a low speed circuit to the fan in response to the actuation of the 30 switch means by one of the damper motors, and circuit means establishing a high speed circuit to the fan in response to the actuation of the switch means by any two of the damper motors when these motors are operated to open 35 their respective dampers.

8. In a heating system, a heater, a motor fan unit having high and low speed circuits for circulating air through said heater and through the spaces to be heated, a damper in each space for 40 controlling the flow of air into said spaces, a separate motor for operating each damper, cam means connected to each motor, a pair of switches operated by each cam means, each switch having a first position when its controlling 45 motor is in a position wherein the damper operated thereby is closed to prevent the admission of air into the respective space, and each switch having a second position when its controlling motor is in a position wherein the damper operated 50 thereby is open to admit air into the respective space, means preventing operation of said motor fan unit when all of said switches are in the first positions, means connecting the low speed circuit of said motor fan unit to a source of power in response to the movement of a single pair of switches to the second position, and means connecting the high speed circuit of said motor fan unit to a source of power in response to movement of more than one pair of switches 55 to the second positions.

9. In a heating system, a heater, a motor fan unit having high and low speed circuits for circulating air through said heater and through

the spaces to be heated, a damper in each space for controlling the flow of air into said spaces, a separate motor for operating each damper, temperature responsive means in each space controlling the operation of the respective damper 5 motor, a pair of cams operated by each motor, a switch operated by each cam, each switch having a first position when its controlling motor is in a position wherein the damper operated thereby is closed to prevent the admission of air into 10 the respective space, and each switch having a second position when its controlling motor is in a position wherein the damper operated thereby is open to admit air into the respective space, means preventing operation of said motor fan 15 unit when all of said switches are in the first positions, means connecting the low speed circuit of said motor fan unit to a source of power in response to the movement of a single pair of switches to the second positions, and means connecting the high speed circuit of said motor fan unit to a source of power in response to movement of more than one pair of switches to the 20 second positions.

10. In a conditioning system, means for causing a forced circulation of fluid through a plurality of spaces to be conditioned at varying rates of flow, means controlling the admission of fluid to each space, means operating said controlling means, space condition responsive means controlling said operating means, switch means, operated by said operating means, controlling a circuit through said fluid circulating means to cause operation of said means to circulate fluid at a low rate when the controlling means is operated to admit air to one space only, and controlling a second circuit through said fluid circulating means to cause operation of said means to circulate fluid at a high rate when the controlling means is operated to admit fluid to any 25 two or more spaces.

11. In a conditioning system, means for causing a forced circulation of fluid through a plurality of spaces to be conditioned at varying rates of flow, said spaces including one space requiring more fluid than the others, means controlling the admission of fluid to each space, means operating said controlling means, space condition responsive means controlling said operating means, switch means, operated by said operating means, controlling a circuit through said fluid circulating means to cause operation of said means to circulate fluid at a low rate when the controlling means is operated to admit fluid to any single space except said one space, controlling a second circuit through said fluid circulating means to cause operation of said means to circulate fluid at a high rate when the controlling means is operated to admit fluid to more than one space, and also when the controlling means is operated to admit fluid to said one space only.

CLARENCE W. NESSELL.
